UNITED STATES PATENT OFFICE.

EDWIN FORREST SHAFFER, OF COLUMBUS, OHIO.

DESIGN FOR AN INK-WELL.

53,644.

Specification for Design.

Patented July 22, 1919.

Application filed May 12, 1919. Serial No. 296,703. Term of patent 14 years.

To all whom it may concern:

Be it known that I, EDWIN FORREST SHAFFER, a citizen of the United States, residing at Columbus, in the county of Franklin and State of Ohio, have invented a new, original, and ornamental Design for an Ink-Well, of which the following is a specification, reference being had to the accompanying drawing, forming part thereof.

Figure 1 of the drawing shows a rear

I claim:

The ornamental design for an ink well as shown.

In testimony whereof I affix my signature hereto.

EDWIN FORREST SHAFFER.
